Inventor

Alexander Saxe

By his Attorney

Edmund Phelps Warren

UNITED STATES PATENT OFFICE.

ALEXANDER SAXE, OF NEW YORK, N. Y.

TOOTHBRUSH.

Application filed February 25, 1921. Serial No. 447,868.

To all whom it may concern:

Be it known that I, ALEXANDER SAXE, a citizen of the United States, and resident of the borough of Manhattan, county of New York, State of New York, have invented certain new and useful Improvements in Toothbrushes.

This invention relates to improvements in toothbrushes and has for its principal object to provide a toothbrush having a swivel head which is arranged in such a manner as to automatically lock in such position as to permit the handle to extend from said brush head in a plane with the longitudinal axis thereof or at right angles thereto.

Therefore as another object this invention contemplates the provision of a brush wherein it is possible to change the position of the head to permit the vertical movement of the brush with ease.

With these and other objects in view the invention consists of a novel construction, combination and arrangement of parts which will be fully set forth in the following specification, claimed and illustrated in the accompanying drawings in which:—

Fig. 1 is a plan view of the brush illustrating the handle lying in a plane with the head.

Fig. 2 is a view similar to Fig. 1 showing the handle turned at right angles to the head.

Fig. 3 is a fragmentary side view of the brush showing portions thereof in section, to more clearly illustrate the details of the construction, and

Fig. 4 is a plan view of the brush head showing the handle removed.

Referring to the drawings in detail the numeral 5 designates in its entirety the brush head comprising a base 6 into which the bristles 7 are secured by vulcanizing or any other suitable manner. This base 6 is provided at its center with an upwardly extending pin 8 which projects in a direction opposite the bristles and embedded in the upper side of the base is a ring formed with sockets 9 which are arranged as shown in Fig. 4 to hold the handle in its various adjusted positions.

The handle previously referred to is designated by the numeral 10 and is provided ad-

jacent one end with a recess 11 having a central bore 12 arranged therein for the reception of the pin 8. Embedded in the under side of the handle and projecting from the surface thereof for a short distance are pins 13 which are adapted to enter the sockets 9 to lock the handle against accidental rotation. Seated in the recess 11 is a volute spring 14 the upper and smaller end of which abuts the washer 15 which is riveted to the upper end of the pin 8 as will be clearly seen upon reference to Fig. 3.

In assembling the device the pin 8 is passed through the opening 12 after which the spring 14 is slipped over the end of the pin and the washer then placed over the pin so that it rests upon the spring. The pin is then slightly headed to retain the washer in place and it will be obvious that upon forcibly turning the brush head relative to the handle, the pins 13 will enter the sockets and lock the head against accidental movement. It will thus be seen that the brush may be used in the ordinary manner. The head may be turned to extend transversely of the handle to facilitate the brushing of the teeth vertically.

While in the foregoing there has been shown and described a preferred embodiment of this invention, it is to be understood that certain minor changes in the details of construction may be resorted to without departing from the spirit and scope of the invention as claimed.

What is claimed is:

1. A tooth brush having a head and handle, said handle being provided with a perforation extending therethrough and terminating in an enlarged recess, a pivot pin having one end secured in said head and extending through the perforation of said handle and into said recess, a disc upon said pivot pin, a volute spring between said disc and said handle to urge said handle toward said head, and means between said head and handle and controlled by said spring for arresting the relative movement of said head and handle at predetermined points.

2. A tooth brush having a head and handle, an annular ring arranged in said head, said ring being provided with recesses and said handle being provided with an enlarged

recess entering from the outer surface thereof and a perforation communicating with said recess and extending through said handle, a pivot pin extending from said handle into said enlarged recess, a disk secured upon said pin, a resilient member between said disk and said handle to retain said handle closely adjacent said head and a plurality of pins in said handle adapted to engage in the recesses in said annular ring. 10

Signed at New York in the city, county and State of New York this 29th day of January, 1921. ALEXANDER SAXE.
